UNITED STATES PATENT OFFICE.

ARTHUR J. ZIPP, OF CENTRAL LAKE, MICHIGAN.

LOGGING GRAPPLE OR TONGS.

1,266,650.

Specification of Letters Patent. Patented May 21, 1918.

Application filed October 30, 1917. Serial No. 199,256.

To all whom it may concern:

Be it known that I, ARTHUR J. ZIPP, a citizen of the United States, residing at Central Lake, in the county of Antrim and State of Michigan, have invented certain new and useful Improvements in Logging Grapples or Tongs, of which the following is a specification.

This invention relates to logging grapple 10 or tongs.

The objects of this invention are:

First, to provide an effective logging grapple means for recovering submerged logs from the bottoms of lakes and rivers.

Second, to provide means of the character described comprising a pair of logging tongs with a sliding support for holding the tongs in position to engage with the logs at the bottom of the lake or river as 20 the tongs are drawn along.

Further objects, relating to structural details, will definitely appear from the detailed description to follow.

I accomplish the objects of my invention 25 by the devices and means described in the following specification. The invention is clearly defined and pointed out in the claims.

A structure which is a preferred embodiment of my invention is clearly illustrated 30 in the accompanying drawing forming a part of this specification, in which:

Figure I is a side elevation of my improved logging tongs.

Fig. II is likewise a side elevation of my improved tongs showing the cable connections thereto and the tongs in open position.

Fig. III is a plan view.

Fig. IV is an enlarged sectional detail 40 taken on a line corresponding to line 4—4 of Fig. I.

Fig. V is an enlarged detail of the lower end of the rear tong.

Fig. VI is an enlarged detail taken on a 45 line corresponding to line 6—6 of Fig. V.

Fig. VII is an enlarged detail of a modification of the lower end of the rear tong corresponding to the view of Fig. V.

In the drawing, similar reference characters refer to similar parts throughout the several views, and the sectional views are taken looking in the direction of the little arrows at the ends of the section lines.

The bottoms of many lakes and rivers 55 which have formed water courses for log-

ging operations are covered with, or have thousands of logs embedded therein. The greater proportions of these logs are hard wood, which, on account of their high specific gravity, become water-logged in a comparatively short time to such an extent that they sink to the bottom of the water courses over which they are being transported. The water acts as a preservative and the recovery of these logs is today of considerable 60 commercial importance. The object of this invention is, therefore, to provide means for easily recovering these sunken logs which either lie upon the bottoms of the lakes and streams, or may be partially embedded 70 therein.

Referring to the drawing, 1 and 2 indicate a pair of logging tongs pivotally mounted upon the bolt 3. Rings 4 are pivotally secured to the upper end of each of 75 the tongs 1 and 2 and a cable receiving ring 5 passes through the rings 4. The structure thus described is ordinarily known as a logging, or skidding tongs.

I provide a sliding support for the tongs, 80 the support in the structure illustrated comprising a pair of runners 6 to the forward ends of which at 7' are pivoted arms 7. These arms extend upwardly and inwardly, as shown in Fig. III, to receive the pivot 85 bolt 3 of the tongs. The upper ends of these arms 7 are provided with holes in which the collars 8 on the bolt 3 are disposed,—see Fig. IV. Plates 9 are bolted to the runners 6, there being a wooden filler 90 10 between the runners 6 and the plates 9. A spreader link 11 has its outer ends pivotally connected with the said runners. These runners and the fillers 10 may be made entirely of metal plates of integral 95 construction, a simple modification not necessary to illustrate.

A pointed log engaging finger 12 slides in guides 13 on the prong of the rear tong and is urged forwardly by the spring 14. 100 Normally the end of this log engaging finger projects beyond the end of the prong of the rear tong.

In Fig. VII, I show a modification of this pointed engaging finger 19 pivoted at 105 20 and held yieldingly in place by spring 21, a cord loop 22 being provided to keep the parts in coöperative relation.

A ring 15 pivotally secured to the lower end of the tong 1 receives the end of the 110

- cable 16 which is used for dragging the tongs along the bottom of the lake or river, the upper end of the cable 16 being connected with a tug, or other similar structure.
- 5 A ring 17 secured to the lower end of the tong 2 forms a connection with the cable 18 which can be used for retracting the tongs to disengage the same or whenever desired.
- 10 In use the tongs are lowered to the bottom of the lake or river by the cable 19 and are then drawn over the bottom by means of the cable 16. If the prong of the rear tong should engage the log L in the upper position, indicated in dotted outline in Fig. II, the cable 16 is slackened off and when a pull is exerted on the cable 19 the tong 1 engages with the log on the opposite side. The log is then raised by the cable 19. If, however, 20 the log is partially embedded in the bottom of the lake or river or, for some other reason, it occupies the position relative to the prong of the rear tong shown in dotted outline at L' this tong would very likely slide over the log if it were not for the provision of the log engaging finger 12. This finger is sharpened to a point and, when it engages a log, it arrests the movement of the tongs whereupon the tong 1 is immediately 25 lowered by slackening on the cable 16 and pulling on the cable 19 to engage the log. This operation causes the prong of the tong 2 to engage with the side of the log and the log can then be raised.
- 30 While I have described the preferred embodiment of my invention in detail it is capable of other adaptations and modifications within the scope of the following claims.
- 35 Having thus described my invention, what I claim as new and desire to secure by Letters Patent, is:—
- 40 1. In a structure of the class described, the combination with a pair of pivoted logging tongs, of a sliding support therefor comprising a pair of runners, a spreader link connecting said runners, upwardly extending arms pivotally secured to said runners for supporting the pivot of said tongs, means for connecting a cable to the upper end of said tongs, means for connecting a cable to the lower end of each of said tongs, and a spring pressed log engaging finger secured to and projecting beyond the prong of the rear tong.
- 45 2. In a structure of the class described, the combination with a pair of pivoted logging tongs, of a sliding support therefor comprising a pair of runners, a spreader link connecting said runners, upwardly extending arms secured to said runners for supporting the pivot of said tongs, means for connecting a cable to the upper end of said tongs, means for connecting a cable to the lower end of each of said tongs, and a spring pressed log engaging finger secured to and projecting beyond the prong of the rear tong.
- 50 3. In a structure of the class described, the combination with a pair of pivoted logging tongs, of a sliding support therefor comprising a pair of runners, upwardly extending arms pivotally secured to said runners for supporting the pivot of said tongs, means for connecting a cable to the upper end of said tongs, and means for connecting a cable to the lower end of each of said tongs.
- 55 4. In a structure of the class described, the combination with a pair of pivoted logging tongs, of a sliding support therefor comprising a pair of runners, upwardly extending arms secured to said runners for supporting the pivot of said tongs, means for connecting a cable to the upper end of said tongs, and means for connecting a cable to the lower end of each of said tongs.
- 60 5. In a structure of the class described, the combination with a pair of pivoted logging tongs, of a sliding support therefor comprising a pair of runners, upwardly extending arms pivotally secured to said runners for supporting said tongs, means for connecting a cable to the upper end of said tongs, and means for connecting a cable to the lower end of each of said tongs.
- 65 6. In a structure of the class described, the combination with a pair of pivoted logging tongs, of a sliding support therefor comprising a pair of runners, upwardly extending arms on which said tongs are mounted secured to said runners, means for connecting a cable to the lower end of each of said tongs.
- 70 7. In a structure of the class described, the combination with a pair of logging tongs, a support on which said tongs are pivotally mounted in upright position, means for connecting a cable to the upper ends of said tongs, and means for connecting a drag cable to the lower end of the forward tong.
- 75 8. In a structure of the class described, the combination with a pair of logging tongs, of a support on which said tongs are pivotally mounted in upright position, means for actuating said tongs to hold them in either an open or closed position, and means for engaging partially embedded logs comprising a spring pressed log engaging finger slidably secured to and projecting forwardly of the end of the prong of the rear tong.
- 80 9. In a structure of the class described, the combination with a pair of logging tongs, of means for slidably supporting said tongs in upright position, means for actuating said tongs to hold them in either an open or closed position, and means for engaging partially embedded logs.

10. In a structure of the class described, the combination with a pair of logging tongs, of means for slidably supporting said tongs in upright position, drag means adapted to hold said tongs in open position, and an independent hoisting means adapted to close said tongs.
11. In a structure of the class described, the combination of a pair of logging tongs, drag means connected to one of said tongs whereby the tongs are held in open position
- 5
- and means for slidably supporting the tongs in upright engaging position, and hoisting connections independent of said drag means for closing the tongs, coacting as specified. 15
- In witness whereof, I have hereunto set my hand and seal in the presence of two witnesses.
